CLAIM

The ornamental design for a baby sleepsuit with two zips and foldable cuffs, as shown and described.

DESCRIPTION

FIG. 1 is a front view of a baby sleepsuit with two zips and foldable cuffs according the design;

FIG. 2 is a rear view of the baby sleepsuit with two zips and foldable cuffs of FIG. 1;

FIG. 3 is a front view of the lower portion of the baby sleepsuit with two zips and foldable cuffs of FIG. 1;

FIG. 4 is a rear view of the lower portion of the baby sleepsuit with two zips and foldable cuffs of FIG. 1; and, FIG. 5 is a front view of the baby sleepsuit with two zips and foldable cuffs of FIG. 1 shown with the zipper open and the cuffs unfolded.

The medium size dashed lines in the drawings depict fold lines of the cuffs and form part of the claimed design. The small size dashed lines in the drawings depict the stitched seam connecting the zip to the garment and form part of the claimed design.

1 Claim, 5 Drawing Sheets
